[57] CLAIM

The ornamental design for a earmuff headphone, as shown.

DESCRIPTION

FIG. 1 is a front elevational view of the earmuff headphone of the present invention;

FIG. 2 is a rear elevational view of the earmuff headphone of FIG. 1;

FIG. 3 is a left side elevational view of the earmuff headphone of FIG. 1;

FIG. 4 is a right side elevational view of the earmuff headphone of FIG. 1;

FIG. 5 is a top plan view of the earmuff headphone of FIG. 1; and,

FIG. 6 is a bottom plan view of the earmuff headphone of FIG. 1.

The undisclosed views of the inside of the earmuff headphone form no part of the claimed design.
